UNITED STATES PATENT OFFICE.

HARRY S. MOORE, OF CLEVELAND, OHIO.

DESIGN FOR A DISPLAY-CARD.

SPECIFICATION forming part of Design No. 31,212, dated July 11, 1899.

Application filed June 3, 1899. Serial No. 719,316. Term of patent 7 years.

To all whom it may concern:

Be it known that I, HARRY S. MOORE, a citizen of the United States, and a resident of Cleveland, county of Cuyahoga, and State of Ohio, have invented and produced a new and original Design for Display-Cards, of which the following is a specification, reference being had to the accompanying drawing, forming a part thereof, and which represents a view of a display-card embodying my design.

As shown in the drawing, the leading feature of my design consists of a series of rectangularly-shaped spaces divided by well-defined lines of demarcation and traversed diagonally by the representation of a ribbon of sinuous outline.

The card is divided into the rectangular

space *a*, surmounted by two rectangular spaces, which latter are subdivided into spaces *b* and *b'*, respectively, spaces *b'* occupying relatively opposite positions in their respective spaces. Traversing the lower right-hand and the upper left-hand corners, respectively, of spaces *b* and ending in the spaces *b'* is the space *c*, having the form of the representation 25 of a ribbon of sinuous outline.

What I claim is—

The design for a display-card as herein shown and described.

Signed by me this 1st day of June, 1899.
HARRY S. MOORE.

Attest:

D. T. DAVIES,
A. E. MERKEL.
